52,393.

Patented Sept. 10, 1918.

PROPRIETOR

John Herzog.
BY

Geo. B. Willey ATTORNEY.

UNITED STATES PATENT OFFICE.

JOHN HERZOG, OF SAGINAW, MICHIGAN.

DESIGN FOR A PHONOGRAPH-CABINET.

52,393.

Specification for Design. Patented Sept. 10, 1918.

Application filed August 27, 1917. Serial No. 188,535. Term of patent 14 years.

To all whom it may concern:

Be it known that I, JOHN HERZOG, a citizen of the United States, residing at Saginaw, in the county of Saginaw and State of Michigan, have invented a new, original, and ornamental Design for Phonograph-Cabinets, of which the following is a specification, reference being had to the accompanying drawing, forming part thereof.

The figure is a perspective view of a phonograph cabinet illustrating my new design.

I claim:

The ornamental design for a phonograph cabinet as shown.

JOHN HERZOG. [L. S.]

Witnesses:

NELLIE M. ANGUS,
ROY WALLIS.
